[57] CLAIM

The ornamental design for a ski clip, substantially as
shown and described.

DESCRIPTION

FIG. 1 is a perspective view of a ski clip showing my
new design;

FIG. 2 is a front elevational view thereof, the rear eleva-
tion view being identical thereto;

FIG. 3 is a top plan view thereof;

FIG. 4 is a bottom plan view thereof; and,

FIG. 5 is a right side elevational view thereof, the left
side elevation view thereof being identical thereto.
